UNITED STATES PATENT OFFICE.

GEORGE C. SNYDER, OF NEW YORK, N. Y.

COATING DEVICE.

1,391,281.

Specification of Letters Patent. Patented Sept. 20, 1921.

Original application filed January 17, 1919, Serial No. 271,592. Divided and this application filed July 3, 1919. Serial No. 308,582.

To all whom it may concern:

Be it known that I, GEORGE C. SNYDER, a citizen of the United States, residing at 123 West 44th street, New York, in the 5 county of New York and State of New York, have invented certain new and useful Improvements in a Coating Device; and I do hereby declare the following to be a full, clear, and exact description of the invention, 10 such as will enable others skilled in the art to which it appertains to make and use the same.

This invention relates to coating devices particularly adapted for applying a film of 15 liquid to sheets of material.

It is an object of the invention to produce a device of this character in which a sheet may be coated by the simple operation of being drawn over the device. The use of 20 rollers, brushes or similar parts which are usually employed in coating machines is thus avoided. The mechanism is of simple construction, contains few moving parts, 25 may be easily adjusted to apply films of different thickness to sheets of material and possesses other advantages which will appear more clearly from a description of a preferred embodiment. For this purpose the invention has been shown as employed 30 for applying adhesive to a sheet of material preparatory to winding the same upon a mandrel to produce angular hollow ware in accordance with my application Serial No. 271,592 filed January 17, 1919, of which this 35 application is a division. It will be understood, however, that the invention is not limited to the particular application shown, but is of general utility and may be employed for applying liquids other than adhesive to sheets of material which are not 40 to be subjected to a winding operation. In the accompanying drawing:—

Figure 1 is a perspective view of the apparatus having the invention applied thereto;

45 Fig. 2 is a view partly in longitudinal section of the coating device; and

Fig. 3 is a transverse section of the device along the line 3—3 of Fig. 2.

In the drawing, 1 represents a framework 50 or bed upon which is a fixed bearing 2 carrying a shaft 3, the free end of which is supported by a bearing 4 hinged to the framework as at 5. It will be understood that any other suitable type of movable bearing may be used for supporting the free

end of the shaft. The other end of the shaft is provided with one member of a clutch 6, the other coöperating clutch member being mounted upon the end of a shaft 7 provided with a pulley 8 adapted to be 60 driven from any convenient source of power. The clutch 6 is controlled by an arm 9 connected by means of a rod 10 to a handle (not shown) which may be placed in position to be conveniently manipulated 65 by the operator of the machine.

Upon the shaft 3 is mounted a mandrel 11 provided with slightly convex faces. The body portion of the mandrel may be of solid material, or hollow for the sake of economy, 70 and one corner of the body is in the form of a wedge 12 which is attached to the body by a dovetail connection, so that the wedge may be driven out after a form has been wound upon the mandrel, to permit the 75 form to be conveniently removed. As explained in the application referred to above, the curvature imparted to the faces of the mandrel should be sufficient to cause a binding action between the convolutions of material as they are wound upon the mandrel, but should not be so great as to prevent the article from assuming a substantial flat-sided contour when straight edged heads are 80 applied to the ends of the form. 85

The material 13 out of which the articles are formed is preferably supplied in rolls which may be mounted upon a shaft 14 parallel to the shaft 3 and provided at one end with a pulley 15 connected by a crossed belt 16 with a pulley 17 on the shaft 3, so that the shaft 14 is rotated in a direction to unwind material from the supply roll, while the shaft 3 is rotated simultaneously in a direction to wind the material upon the 95 mandrel. As the material is unwound from the supply roll it passes to the bottom of a trough 18. The relation between the mandrel and the supply roll should be such that there will be at all times a certain amount of slack of the material at the bottom of the trough to allow for the variable speed at 100 which the material is wound on the mandrel due to the angular shape of the latter. The material is then carried upwardly over a shelf 19 against which it is pressed by spring fingers 20. To provide for adjusting the tension of the material as it is wound upon the mandrel the spring fingers are mounted 105 upon a pivoted support 21 provided with 110

a depending wedge shaped portion 22 engaged by a cam 23 on a shaft 24 mounted in suitable bearings attached to the shelf 19 and which may be manipulated by a gear 5 and worm arrangement such as is shown in my application referred to above. Instead of the mechanism described, any suitable arrangement for producing tension of the material may be used. After passing 10 over the shelf 19 and under the spring fingers 20 the material passes under a roller 25, then over the coating device of the invention and around another roller 26 from which it passes to the mandrel. In order 15 to change the angle of incidence at which the material passes to the coating device, the roller 25 should possess the capability of vertical adjustment. This may be accomplished by mounting the bearings of 20 the roller in vertical guides 25' with suitable means for holding them in any position.

The device for supplying adhesive to the surface of the material comprises a horizontal pipe 27 screwed into an elbow 28 at one 25 end and at the other end mounted in a suitable support 29. The elbow 28 is connected to a pipe 30 which in turn is connected to a valve 31, located below the level of pipe 27. Adhesive is supplied from the tank 32 30 through a pipe 33 leading to the valve 31. If necessary a burner 34 may be provided to keep the adhesive in liquid condition, or cold adhesive, such as silicate of soda, may be used as a binder. The valve 31 may be 35 manipulated by a rod 35 connected to a handle 36 mounted in convenient position on the framework of the apparatus. The pipe 27 is provided with a longitudinal channel 37 communicating with the interior 40 of the pipe through ducts 38. Extending from the top of the channel 37 in the direction in which the material travels as it is drawn over the pipe are passages 39 through which adhesive may flow from the 45 channel onto the surface of the material. The passages 39 should preferably register with the ducts 38 as shown most clearly in Fig. 2, and have their bottoms tangential to the pipe as shown in Fig. 3. It will be 50 understood that any number of ducts and passages may be employed and that they will be of suitable dimensions to permit the required flow of adhesive.

In forming angular hollow ware by 55 means of the apparatus described above, a roll of suitable material is placed on the shaft 14 and unwound enough to leave some slack at the bottom of the trough. The material is then drawn over the shelf 19 under the fingers 20 which should be adjusted to exert little or no pressure at this time. The material is then carried under roller 25, over the adhesive supply pipe 27 and around roller 26 to the mandrel 11. As the 60 strip of material is drawn over supply pipe

27 adhesive should be permitted to flow in order that the outer face of the first convolution of material shall be coated so that the second convolution will be united to it. In passing over roller 26 the material is turned so that the surface which has been coated with adhesive comes uppermost, in proper position to be wound upon the mandrel so as to prevent the adhesive from sticking to the mandrel and leave the inside 75 of the form clean.

After the end of the strip of material has been placed upon the mandrel, the latter may be started into operation by manipulation of the clutch 6, it being understood 80 that at this time the bracket 4 is in position to support the free end of shaft 3. When the winding operation begins, the spring fingers 20 should be adjusted to produce the required degree of tension as the 85 materials wound upon the mandrel. On account of the convexity of the faces of the mandrel successive convolutions of the material are firmly united to the proceeding convolutions, and owing to the greater distance of the corners of the mandrel from the shaft, there will be an increased binding effect between the layers of material at these 90 points and they will be united into a compact mass to give strong rigid corners to the 95 finished article.

During the winding operation adhesive is supplied to the material from the pipe 27 through the ducts and passages 38 and 39, and the amount of adhesive applied to the 100 material may be adjusted to the desired quantity by a slight rotation of the tube 27 about its axis. The screw connection between the pipe and the elbow 28 will permit of this adjustment, but it will be understood that any other arrangement may be employed for permitting a slight rotation of the tube with respect to the piping system through which adhesive is supplied. If, instead of occupying the relation with respect 105 to the sheet of material shown in Fig. 3, the tube 27 is rotated slightly in a clockwise direction, the relation of the channel and the passages with respect to the material will be such that a greater quantity of adhesive 110 will be applied to the surface of the material. If the pipe 27 is rotated in the opposite direction, the relation will be changed so that less adhesive will be supplied. The arrangement thus permits one to obtain variations in the thickness of the film applied to the material by manipulation of the pipe 27, which may be conveniently performed without requiring any other adjustments of the apparatus.

Further adjustment may be obtained by 120 altering the angle of incidence at which the material passes to the coating device, by changing the elevation of roller 25. If the changes in the amount of adhesive to be ap- 125 130

plied to the material cannot be produced by the adjustment of the apparatus as described above, other pipes provided with channels, ducts and passages of different dimensions may be easily substituted for the original pipe, so that a wide range of adjustability may be obtained with the apparatus.

The operation of winding the material upon the mandrel is continued until the walls of the article are of the required thickness, when the supply of adhesive is cut off. By arranging the valve 31 below the level of pipe 27, the supply of adhesive ceases as soon as the valve is closed, there being no tendency for the adhesive remaining in the pipe 27 to continue to flow on to the material as would be the case if the valve 31 were located above the level of the pipe.

When the winding operation is completed the material is severed, preferably along a line adjacent to one of the corners of the wound body. Any adhesive on the outer face of the body will finally dry and form a protecting coating. When the formation of the body has been completed the bracket 4 is swung out of the way, the wedge 12 is driven out and the body may be then removed from the mandrel for subsequent treatment.

The above description shows one way in which the device of this invention may be employed, but it will be understood that it is of general utility and may be used for coating any kind of material with any kind of liquid, and also that various changes may be made in the details of construction of the apparatus without departing from the principle of the invention as defined in the appended claims.

I claim:

1. In apparatus for coating sheet material with liquids, a member over which the material is adapted to be drawn and having an opening along its upper side through which the liquid may flow to the surface of the material, and a valve placed below the level of the opening for controlling the flow of liquid therethrough.

2. In apparatus for coating sheet material with liquids, a member over which the material is adapted to be drawn and having an opening through which liquid may flow to the material, a valve placed below the level of the opening and adapted to control the flow of liquid to the member, and a member around which the sheet material travels after it has been coated in order to bring the coated side of the material uppermost.

3. In apparatus for coating sheet material with liquids, a member over which the material is adapted to be drawn and having

passageways through which the liquid flows to the material, and means for changing the angle of incidence of the material, with respect to the passageways to regulate the amount of liquid applied to the surface of the material.

4. Apparatus for coating the underside of sheet material with a continuous film of adhesive, comprising a pipe provided with a continuous channel along the top thereof in communication with the interior of the pipe, the channel being of a length about equal to the width of the sheet material, the top of the pipe being provided with laterally extending passages in communication with said channel.

5. In apparatus for coating sheet material with liquids, a tubular member provided with a longitudinal channel along its outer face, ducts between said channel and the interior of the member, and passages extending from the top of the channel at right angles thereto and registering with the ducts.

6. In apparatus for coating sheet material with liquids, a tubular member provided with a longitudinal channel along its outer face communicating with the interior of the member, and passages extending from the top of the channel in the direction in which the material is drawn over the member, means for supplying liquid to the member and a connection between the means and the member to permit the member to be rotated about its longitudinal axis to vary the amount of liquid applied to the sheet material.

7. In apparatus for coating sheet material with liquids, a tubular member having apertures communicating with the interior of the member and passages extending from the apertures in the direction in which the material is drawn over the member, and means for supplying liquid to the member comprising a part to which the member is secured, so that the member may be rotated about its axis to vary the quantity of liquid supplied through the passages to the sheet material as it is drawn over the member.

8. In apparatus for coating sheet material with liquids, a tubular member provided with a longitudinal channel along its outer face having communication with the interior of the member, passages extending from the top of the channel in the direction in which the material is drawn over the member, a reservoir for holding liquid, a conduit for conveying liquid from the reservoir to the tubular member, a portion of said conduit being located below the level of the tubular member, and a valve in the said portion of the conduit.

In testimony whereof I affix my signature.

GEORGE C. SNYDER.
